See & M. Calb Pitts.

UNITED STATES PATENT OFFICE.

DOUGLAS F. FESLER, OF EVANSTON, ILLINOIS, ASSIGNOR TO THE BASSICK MANUFACTURING COMPANY, OF CHICAGO, ILLINOIS, A CORPORATION OF DELAWARE.

LUBRICATING DEVICE.

1,388,939.

Specification of Letters Patent. Patented Aug. 30, 1921.

Original application filed November 18, 1918, Serial No. 262,930. Divided and this application filed August 25, 1920. Serial No. 405,979.

To all whom it may concern:

Be it known that I, DOUGLAS F. FESLER, a citizen of the United States, residing at Evanston, in the county of Cook and State 5 of Illinois, have invented a certain new and useful Improvement in Lubricating Devices, of which the following is a full, clear, concise, and exact description, reference being had to the accompanying drawings, forming 10 a part of this specification.

My invention relates to improvements in lubricating devices and is particularly concerned with improvements in devices adapted and intended to be used in connection 15 with a well-known system of lubrication which comprises, among other things, a plurality of nipples or coupling members adapted to be secured to the bearings to be lubricated and a lubricant compressor 20 having a coupling member adapted to be successively detachably connected with said nipples or coupling members.

The objects of my invention are,

First, to provide devices for replacing the 25 nipples of the above described system, comprising means for receiving and holding a considerable supply of lubricant under pressure, the said means being in communication with a member connected with the bearing and adapted to be connected with the lubricant compressor so that the receiving 30 means can be filled by means of a compressor and will, in turn, discharge its contents into the bearing after the compressor has 35 been detached from the device.

Second, to provide a device of the character described which is simple in construction and economical to manufacture, and

Third, to provide a device of the character 40 described which can be easily dismantled for the purposes of cleaning or repairing.

Other objects will appear as this description progresses, reference being had to the accompanying drawings in which,

45 Figure 1 is a plan view thereof, and Fig. 2 is a central longitudinal section.

In both figures, similar reference characters will be used for referring to similar parts.

50 My improved device comprises a central tube 5, one end of which is provided with screw threads, by means of which it can be attached to a bearing to be lubricated and the other end of which is provided with a

closure 7 which is yieldingly held in its 5 closed position by means of a spring 8. The lower end of the spring 8 rests upon the pin 9 which extends through the tube and the opposite ends of which extend outwardly from the sides of the tube. The said pin 60 comprises means for making a detachable connection with a lubricant compressor such as that disclosed in my co-pending application, Serial No. 262,930 filed November 18, 1918, of which this is a division.

Surrounding the tube 5, and concentric therewith is a cylindrical container 10, one end wall 11 of which is provided with screw threads for co-acting with the screw threaded end 6 of the tube to secure the container 70 thereto. The opposite end of the container is closed by a cap 12 having screw-threaded engagement with the adjacent end of the container and provided with a central aperture 13 through which the tube projects. 75 The tube 5 is provided with a plurality of openings 14 adjacent the inner side of the end wall 11 which establish communication between the interior of the tube and the space between the end wall 11 and the 80 plunger which comprises the cup leather 15 and the follower plate 16. The last two mentioned members are provided with central apertures for receiving the tube 14. A spiral spring 17 interposed between the follower plate 16 and the cap 12 provides means for yieldingly urging the plunger toward the end wall 11. The spring is so designed 85 that when the plunger is in its uppermost position, that is, when it lies adjacent the cap 12, the convolutions of the spring 17 will all lie in a common plane and rest against the inner side of the cap 12 thus forming a firm support for the plunger. If desired, a rod 18 may be secured to the 90 follower 16 and project through an opening in the cap 12 to indicate the amount of lubricant in the container.

In use, when it is desired to supply lubricant to a bearing equipped with my improved device, the coupling on the discharge conduit of the lubricant compressor is connected with the outer end of the tube 5 as described in my co-pending application above referred to and the compressor is operated 100 to force lubricant into the tube under pressure. The pressure of the spring 17 is so related to the passage of lubricant between

the surfaces of the bearing to be lubricated that the lubricant will, at first, be forced through the openings 14 into the space between the end wall 11 and the plunger, and 5 will raise the plunger against the pressure of the spring until the spring has been flattened out against the cap 12 thus preventing any further movement of the plunger. Upon 10 then increasing the pressure on the lubricant, it will be forced between the surfaces to be lubricated, thus displacing the used lubricant from the bearing and replacing with fresh lubricant. At this stage the compressor is detached from the tube 5 whereupon 15 the spring 17 will act to continuously supply lubricant to the bearing under a reduced pressure.

While I have described the details of construction of the preferred embodiment of my 20 invention, it is to be clearly understood that my invention is not limited to these details but is capable of other adaptations and modifications within the scope of the appended claims.

25 Having thus described my invention, what I claim is:—

1. A lubricating device comprising a container, the opposite ends of which are provided with registering openings, a tube 30 extending through said container and said openings, one end of said tube being provided with an outwardly closing closure and means for making a detachable connection with a lubricant compressor, the other end 35 of said tube being provided with means for connecting said device with a bearing to be lubricated, the wall of said tube being provided with an opening adjacent the inner side of one end wall of said container, a 40 plunger mounted in said container and a spring for urging said plunger toward said last-mentioned end wall.

2. A lubricating device comprising a container, the opposite ends of which are provided with registering openings, a tube 45 extending through said container and said

openings, one end of said tube being provided with means for making a detachable connection with a lubricant compressor, the other end of said tube being provided with 50 means for connecting said device with a bearing to be lubricated, the wall of said tube being provided with an opening adjacent the inner side of one end wall of said container, a plunger mounted in said container and means for urging said plunger toward said last-mentioned end wall.

3. Means for supplying lubricant to a bearing comprising a tube having means at one end for making connection with a bearing, the other end of said tube being provided with an outwardly closing closure and means for making a detachable connection with a lubricant compressor, and means surrounding said tube and in communication 60 therewith for receiving and discharging lubricant through said tube under pressure.

4. Means for supplying lubricant to a bearing comprising a tube having means at one end for making connection with a bearing, the other end of said tube being provided with an outwardly closing closure and means for making a detachable connection with a lubricant compressor and means in 70 communication with said tube for receiving and discharging lubricant through said tube under pressure.

5. Means for supplying lubricant to a bearing comprising a tube having means at one end for making connection with a bearing, the other end of said tube being provided with means for making a detachable connection with a lubricant compressor and means in communication with said tube for receiving and discharging lubricant through 75 said tube under pressure.

In witness whereof, I hereunto subscribe my name this 21st day of August, 1920.

DOUGLAS F. FESLER.
